UNITED STATES PATENT OFFICE.

JOSEPH BECK, OF NEWARK, NEW JERSEY, ASSIGNOR OF TWO-THIRDS TO SIGISMUND E. SIMON AND LEVY MAYBAUM, OF SAME PLACE.

RETORT FOR MAKING BISULPHIDE OF CARBON.

SPECIFICATION forming part of Letters Patent No. 464,747, dated December 8, 1891.

Application filed February 18, 1891. Serial No. 381,909. (No model.)

To all whom it may concern:

Be it known that I, JOSEPH BECK, a citizen of the German Empire, residing at the city of Newark, county of Essex, and State of New Jersey, have invented certain new and useful Improvements in Retorts for Making Bisulphide of Carbon, of which the following is a specification.

This invention relates to an improved retort for making bisulphide of carbon by which the yield of bisulphide of carbon is increased and the exchanging of worn-out retorts facilitated, which was connected with considerable expense and loss of time in the retorts heretofore used; and the invention consists of the combination, with a retort for evaporating sulphur, which is located in a separate furnace, of a retort filled with charcoal and a pipe for connecting the evaporating-retort with the charcoal-retort, said connecting-pipe being located outside of the furnace and provided with a slide-piece for shutting off the connection between the retorts.

The invention consists, secondly, of a charcoal-retort having a flange at its upper end, said flange resting on transverse bars supported by exterior upright bars of the furnace, which has a temporary front wall, so as to facilitate the exchanging of worn-out retorts.

In the accompanying drawings, Figure 1 represents a vertical longitudinal section of my improved retort for making bisulphide of carbon. Fig. 2 is a horizontal section on line 2 2, Fig. 1. Fig. 3 is a detail side view of the retort for distilling the sulphur. Fig. 4 is a front elevation of a modified form of apparatus, showing two charcoal-retorts connected with one evaporating-retort; and Fig. 5 is a vertical transverse section on line 5 5, Fig. 4, showing the connection of the charcoal-retort with the condenser.

Similar letters of reference indicate corresponding parts.

Referring to the drawings, A represents a furnace, which is open in front, so that it is U-shaped in plan, and which is provided with a grate a and an arch a' above the grate, on which arch rests a cast-iron retort C, preferably made of L shape. The lower part of the retort C extends in forward direction through the front wall of the furnace, which is closed

temporarily in front of the upper part of the retort by suitable brick-work. Around the retort are arranged flues for the products of combustion, said flues communicating with a suitable chimney. In the front wall of the lower part of the retort C is arranged a hand-hole and hand-hole cover for cleaning the interior of the retort. The retort C is provided at its upper part with an annular flange b, which rests on transverse wrought-iron bars d, that are supported by vertical bars d'. The transverse bars d are threaded at the ends, which pass through the vertical bars d', wherein they are removably held by suitable screw-nuts d², as shown in Fig. 1. The retort C is supported on the transverse bars d, so that the retort can freely expand by springing the bars and the retort be readily removed from the furnace A (the front bar d and the front wall of the furnace being removed) when it is necessary to exchange a worn-out retort and replaced when the new retort is placed in position. The retort C is provided at its upper end with a charging-funnel and valve made of the usual construction.

The L-shaped retort C is charged with charcoal, which by the fire below the retort is heated to incandescence, the sulphur vapors being conducted through the charcoal, so as to form vapors of bisulphide of carbon. The sulphur-vapors are supplied from a separate retort D, which is supported in a separate furnace B and connected by a pipe E with the charcoal-retort C, the pipe E being provided with a slide s for shutting off the connection with the evaporating-retort D when necessary.

The sulphur-retort D is provided in its front wall with a hand-hole and hand-hole cover like the retort C, and at its rear part with a funnel-shaped supply-hopper, through which the sulphur is inserted into the retort. The slide s is preferably made of good sheet-iron that is covered with a suitable asbestos preparation or with aluminium, as these substances are capable of resisting the corroding action of the sulphur-vapors, while they permit the easy movement of the slide.

The connecting-pipe E, that connects the front part of the evaporating-retort D with

the front part of the lower portion of the retort C, is located outside of the furnace-walls, so as to protect it against the action of the fire and prevent its too rapid deterioration by 5 the influence of the sulphur vapors passing through the same.

It is preferable to arrange a charcoal-retort at each side of the sulphur-evaporating retort, as thereby the distillation of the sulphur can 10 be made continuous, as when one retort is charged the vapors can be conducted into the other retort C by means of the slide s, and so on alternately.

In Fig. 1 the connection of the evaporating- 15 retort with a single charcoal-retort is shown, while in Fig. 4 the evaporating-retort is shown as connected with two charcoal-retorts C.

The vapors of bisulphide of carbon, which are formed by the contact of the sulphur vapors with the incandescent charcoal in the retort C, are conducted from the upper part of the same through a pipe F to a condenser, which is formed of vertical pipes G and K, the lower parts of which terminate in closed 20 receptacles L and M for the liquid bisulphide of carbon. The pipe K is connected at its upper end with the pipe G and surrounded by a cooling-jacket K', that is supplied with water at the upper end, while an outlet-pipe 25 conducts off the water at the lower end. The liquid bisulphide of carbon collected in the closed receivers L and M is drawn by suitable faucets o, while the non-condensing vapors—such as sulphuret hydrogen—are conducted 30 off through a pipe N from the receiver M. A wall W separates the retorts from the condensers, as shown clearly in Fig. 5.

The advantages of my improved retort for 35 making bisulphide of carbon are that by arranging a separate retort for the sulphur vapors a more effective utilization of the sulphur and a greater yield of bisulphide of carbon is obtained, as the vapors are combined in a more effective manner with the incandescent

charcoal, and as the operation can be more 45 quickly and conveniently interrupted. Secondly, that by arranging two or more retorts in connection with the evaporating-retort the distillation of the sulphur can be carried on continuously and the formation of bisulphide 50 of carbon be also made continuous, as when one retort is charged with charcoal the other is supplied with sulphur, and vice versa; and, thirdly, that by suspending the retorts from a supporting-frame they can evenly expand 55 and do not wear out at the bottom, while they can also be more conveniently removed from the surrounding walls of the furnace whenever a retort is worn out by use and replaced by a new one.

If the retorts were walled up, it is obvious they could not expand without spreading the walls and injuring the furnace, whereas the cross-bars spring slightly and permit such expansion. Furthermore, the furnace being U- 65 shaped in plan, when the front bar d is removed the retort can be withdrawn bodily from the furnace, as will be clear.

Having thus described my invention, I claim as new, and desire to secure by Letters 70 Patent—

The combination, with a furnace of approximate U shape in plan, upright bars at the sides of said furnace, cross bars having threaded ends passing through said upright bars, and 75 nuts on said ends, of an L-shaped retort located in said furnace, with its lower end projecting through the front removable wall thereof, and an annular flange on said retort resting on said cross-bars, substantially as 80 described.

In testimony that I claim the foregoing as my invention I have signed my name in presence of two subscribing witnesses.

JOS. BECK.
